UNITED STATES PATENT OFFICE.

THEODORE W. EISENTRAUT, OF FREDONIA, WISCONSIN.

CANNING MACHINE.

Application filed October 9, 1925. Serial No. 61,481.

This invention relates to canning machines, and is particularly directed to a packer attachment for such machines.

In canning machines adapted to handle vegetables and place them in cans, it is the usual practice to remove the cans from the canner and, thereafter, fill them with brine or other solution. When it is attempted to apply the brine to the filled cans in the canner, it has been found that the brine flows into the cans and when removed from the canner washes the vegetables out of the cans.

This invention is designed to provide a packer attachment for canning machines which will pack the vegetables into the cans in a very rapid and effective manner, and which may be applied to the ordinary canning machines with a minimum of change.

Further objects are to provide a packer for a canning machine which will pack the vegetables into the can and permit the subsequent filling of the cans with brine or other solutions without danger of washing the vegetables from the cans.

An embodiment of the invention is shown in the accompanying drawings, in which:—

Figure 1 is a plan view of a canning machine with the packer in position.

Figure 2 is a side elevation partly broken away of the structure shown in Figure 1.

Figure 3 is an enlarged sectional view on the line 3—3 of Figure 2, showing in detail the construction of the plunger.

Figure 4 is a rear view of the structure shown in Figure 1.

Figures 5, 6 and 7 are diagrammatic views showing successive positions of the plunger and the can upon which it is to operate.

Referring to the drawings, it will be seen that the usual type of canning machine has been illustrated in which the cans are fed by means of the curved rotor 1 beneath the feeding ring 2, such ring passing beneath the member 3 which receives the lower end of the vegetable hopper.

It is to be noted that the drum 1 is provided with the usual worm tooth 4 which engages a single can at a time and places it

beneath the ring 2 in the usual manner. 50 This drum is driven by means of a pulley 5 controlled by a clutch 6 as in the customary practice.

The hopper has not been shown in the drawings nor the chute which delivers the 55 cans to the drum 1 as these are conventional and well understood constructions.

Further it is to be noted from Figures 2 and 4 that the usual adjusting mechanism controlled by the hand wheel 7 is employed 60 for adjusting the position of the parts for cans of different sizes. The cans are removed from the canning machine by means of the usual star wheel 8, as shown in Figure 1.

The packer comprises a shaft 9 mounted below the body of the machine and connected to the shaft 10 of the drum 1 by means of sprocket wheels 11, said sprocket wheels being of the same diameter to insure similar speeds of rotation for the shafts 9 and 10. The shaft 9 projects to the rear of the machine and is carried in a suitable bracket 12 adjacent such end. It is provided with a crank disk 13 having a crank pin 14. This 75 crank pin is connected by means of a pitman 15 with a rocking lever 16 whose end is carried by means of a standard 17 secured to the central portion of the machine, as shown in Figures 1 and 2. The outer or free end 80 of the lever 16 is guided by means of the guiding bracket 18 (see Figure 4.)

A plunger, indicated generally at 19, is carried by the lever 16 and hangs downwardly over the ring 2. This plunger has its 85 body portion recessed, as indicated at 20, and a pin 21 is slidably mounted in such recess. This pin is prevented from moving beyond a predetermined distance by means of a slot formed therein and cooperating 90 with a pin 23 carried by the body portion of the plunger. The rod 21 is provided with a fixed collar 24, and a spring 25 is interposed between the body portion of the plunger and the collar, such spring having a 95 predetermined tension adapted to operate successfully upon the particular material handled by the canner. The lower end of

the plunger is provided with a head 26 which is socketed and receives the lower end of the rod 21. This head is adjustable on the rod to accommodate cans of different depths and is locked in position in any suitable manner, as by means of the set screw 27.

From reference to Figure 3, it will be seen that the plunger 19 is loosely mounted upon the lever 16 and is free to rock thereon. It carries a set screw 28 at its upper end which fits within a recess 29 formed in the shaft 16 to thus provide a limit for the lateral rocking motion of the plunger.

The plunger is urged into its forward position towards the approaching can as shown diagrammatically in full lines in Figure 5, by means of a spring 30 coiled about the lever 16 and having its ends fastening respectively, to such lever and to the plunger. Further, a spring 31 is attached to the plunger at one end and to an adjusting screw 32 passing through the pitman 15 at the other end. This yieldingly holds the plunger in position. It is to be noted that the plunger is loosely mounted upon the lever 16 and is adapted to swing longitudinally and laterally. The tension spring 31 tends to hold the plunger in the position shown in Figure 2 although the lever 16 is slanting when it is descending. This insures the correct registration of the plunger with the approaching opening and can. The exact tension of the spring desired to accomplish this result is secured by the adjustment of the screw 32.

In the conventional types of canners, it is the usual practice, as illustrated in Figures 5, 6 and 7, to provide downturned portions 33 forming flanges at each of the apertures in the ring. The material is fed through these apertures from the hopper carried by the hopper holding bracket 3 (see Figure 1). While the ring 2 rotates, the shafts 9 and 10 rotate in a uniform manner and the ring is advanced one aperture for each rotation of the drum 1 in the well known manner of these conventional canners. The shaft 9 therefor rotates one time during the advance of one aperture in the ring 2 and consequently the lever 16 and plunger 19 are reciprocated once for each aperture. The plunger 19 (see Figure 5) is approximately in line with the nearest approaching aperture and as it descends it passes into the advancing aperture, as indicated in Figure 6, and presses the material downwardly, as shown in Figure 7, arriving at its lowest point of travel when the aperture is directly beneath the plunger. Thereafter, the plunger rises while the aperture is passing beyond such plunger. Rocking or lateral motion of the plunger is permitted by means of the spring 30 so that no binding will occur. When the plunger approaches its uppermost limit of travel it pulls out of

the aperture in the ring 2 and swings into its initial position, as shown in Figure 5, ready for the next aperture.

In this manner a very simple mechanism is employed and successively compresses or packs the vegetables or other material within the cans while the ring 2 rotates at a uniform rate. After the material has been packed, the can passes beneath a head 34 (see Figure 1) such head being hollow and supplied by means of a brine pipe 35. Thus the cans are filled with brine without any danger of washing of the vegetables out of the cans as they are securely packed prior to their arrival at the brine filling portion of the machine.

It will be seen that a very simple type of packer has been provided for conventional canning machines, and that this packer may be applied to the machines without altering their construction.

It will be seen further that this packer securely packs material in the can and permits the immediate use upon the canner of a brine filling device without removal of the cans from the canner and without danger of washing the vegetables from the cans. Thus by means of this invention, the action of the conventional canner may be very much extended beyond the mere filling of cans with the material.

It is to be understood that the term brine and also the term vegetables are to be understood as illustrative only and not as limiting terms as used in the specification and claims of this application.

Although the invention has been described in considerable detail, it is to be understood that the invention may be variously embodied and is, therefore, to be limited only as claimed.

I claim:

1. A canning machine adapted to receive and fill cans and advance the filled cans and having a reciprocatory plunger guided into the advancing filled cans, said plunger being mounted for lateral swinging motion to accommodate the advance of the cans.

2. The combination of a canning machine adapted to receive and fill cans, said machine having an advancing ring positioned over the cans and having apertures corresponding to the cans carried beneath the ring, a packer having a reciprocatory plunger mounted for lateral oscillation and having means for reciprocating the plunger through each aperture to compress the material in the cans, and a liquid head mounted above the ring for feeding liquid into the cans after the material has been compressed.

3. The combination of a canning machine adapted to receive and fill cans and having an advancing ring above the cans and provided with apertures corresponding to the cans, driving means for advancing the ring

and cans in a uniform manner, a lever mounted above the ring, a plunger carried by said lever and extending downwardly therefrom and towards said ring and adapted to enter the apertures in said ring, said plunger being adapted to swing laterally of said lever, a crank driven from said driving means and operatively coupled to said lever, and a spring for urging said plunger laterally of said lever. ¹⁰

In testimony that I claim the foregoing I have hereunto set my hand at Fredonia, in the county of Ozaukee and State of Wisconsin.

THEODORE W. EISENTRAUT.
